UNITED STATES PATENT OFFICE.

ALBERT P. MYER, OF MINNEAPOLIS, MINNESOTA, ASSIGNOR TO MINNEAPOLIS HEAT REGULATOR CO., OF MINNEAPOLIS, MINNESOTA, A CORPORATION.

ALARM-CLOCK.

1,331,276.

Specification of Letters Patent. Patented Feb. 17, 1920.

Application filed October 30, 1917. Serial No. 199,239.

To all whom it may concern:

Be it known that I, ALBERT P. MYER, a citizen of the United States, resident of Minneapolis, county of Hennepin, State of Minnesota, have invented certain new and useful Improvements in Alarm-Clocks, of which the following is a specification.

The object of my invention is to provide a time piece in which the main spring operates both the clock and the alarm mechanism and in using the alarm it is only necessary to set the indicator hands for the desired hour to insure its operation when that hour arrives, the winding of an alarm spring usually incident to clocks of this type as generally constructed being entirely avoided and thereby a considerable saving is effected in the number of parts required and the first cost of the clock.

A further object is to provide a time piece of this type in which provision is made for shifting the contact points of a thermostat at a predetermined hour of the day, governed by the position of the indicator hands of the alarm dial.

Other objects of the invention will appear from the following detailed description.

The invention consists generally in various constructions and combinations, all as hereinafter described and particularly pointed out in the claims.

In the accompanying drawings forming part of this specification,

Figure 1 is a rear view of a clock embodying my invention,

Fig. 2 is a sectional view on the line 2—2 of Fig. 3,

Fig. 3 is a side view, partially in section, through the mechanism of the clock,

Fig. 4 is a detail view on the line 4—4 of Fig. 2,

Fig. 5 is a similar view showing the alarm attachment in its released position,

Fig. 6 is a detail view, showing the engagement of the alarm pinion with the gear of the clock mechanism.

In the drawing, 2 represents a clock casing, 3 and 4 the minute and hour hands respectively and 5 a train of gears through which the hands are operated in the usual way. 6, 7 and 8 are partitions within the clock casing, arranged in parallel relation and 9 is a suitable cap or cover for the rear end of the casing. A post 10 is mounted in the partitions 6, 7 and 8

and secured thereto is a main spring 11 arranged within a drum 12 that is loosely mounted upon the post 10. A gear 13 is secured to the drum 12 through which the train of gears 5 is driven. A collar 14 is secured on said post on the opposite side of said drum and is provided with a flange 15. Mounted on the collar 14 is a ratchet wheel 16 and a gear 17 has a flange that is loosely mounted on the collar 14 between a flange 18 and the wheel 16. A spring-pressed pawl 19 is secured to the flange 18 and engages the teeth of the ratchet wheel 16. The gear 17 drives a gear 20 which meshes with a pinion 21 on a shaft 22 and a pinion 23 on a shaft 24 is also driven from the gear 20 (see Fig. 2). A gear 25 is driven from the gear 20 and engages a pallet 26 on which a rod 27 is mounted in position to engage the bent end portion 28 of a spring 29 and thereby be held against vibrating through the movement of the pallet. In clock construction this rod 27 may carry the alarm hammer and when the pallet is released the arm will be vibrated to contact with the bell and sound the alarm. A spring 29 is secured at one end to the partition 7 while its opposite end is free to move back and forth to lock or release the vibrating rod 27. The post 22 is extended through the wall 9 and is provided with a crank arm 30 which may be utilized for shifting the contact points of a thermostat or for closing any other electric circuit.

To provide a half revolution for the crank arm 30 when the alarm mechanism is released, I provide a yoke 31 on the post 24 having inwardly projecting lugs 32 in the path of hands 33 and 34 mounted on a post 35. Secured to said post is a disk 36 having graduations thereon to indicate the hours of the day and also the letters A. M. and P. M. The indicator hands are properly spaced on the disk and secured by a nut 37. The post 35 is provided with a gear 38 that is driven from the train of gears 5, as shown in Fig. 3, the gearing being such that the post will make one complete revolution in twenty-four hours, and during this time the hands 33 and 34 will each contact with one of the lugs 32 and thereby the yoke 31 will be actuated twice each day, being moved from the full line position in Fig. 1 to the dotted line position in the same figure. The inner end of the post 24 is provided with a yoke 39 hav-

ing inwardly projecting lugs provided with tapered surfaces 40. This yoke 39 is mounted so that its tapered surfaces will contact with the spring 29 and move it from the 5 dotted line position in Fig. 4 to the full line position in the same figure, where its end portion 28 will be in the path of the rod 27 and will check vibration of said rod and thereby stop the operation of the gears.

10 The post 24 and the parts mounted thereon have a limited freedom of movement to allow the yoke 39 to release the spring 29 and this movement I accomplish by providing comparatively large spaces between the 15 teeth of the gear 20 to receive the teeth of the pinion 23, so that the said pinion with the post 24 may rock a limited distance between the teeth of the gear 20 sufficient to release the spring 29. This is plainly shown 20 in Fig. 6 where, upon comparison with Fig. 2, it will be noted the pinion has been rotated so that one of its teeth fitting into the recess between the adjacent teeth of the gear 20 has moved from one side of the space to 25 the other and during such movement the yoke 39 has been oscillated sufficiently to disengage its surface 40 from the spring 29 and allow this spring to assume the position shown by dotted lines in Fig. 4 and release 30 the rod 27. This movement of the yoke 39 will take place when the yoke 31 is engaged by one of the hands 33 or 34 and when released the yoke 39 will make a half revolution or until one of the beveled surfaces 40 35 engages the spring 29, when the said spring will be flexed and forced from the position indicated by dotted lines in Fig. 4 to the full line position in the same figure, and when moved to this full-line position the end 40 28 will be in the path of the vibrating rod 27 and will check the movement of the same and through it the operation of the gears will be arrested.

In operation, when one of the hands 33, 45 34 comes in contact with the bent end of the adjacent arm 32 the shaft 24 is partially rotated and carries the bent end 40 from holding contact with spring arm 29 so that said arm will spring to the position shown 50 in dotted lines in Fig. 4 and thus release the pallet arm 27 and permit the alarm to be sounded during the period of time that the bent end of the other arm 39 is being brought into contact with the spring arm 29 and press 55 it so as to bring its bent end 28 into the path of vibration of the pallet arm 27 and thus check the vibration of that arm and the sounding of the alarm. During this period the other arm of the yoke 31 has been 60 brought into position to have its bent end to be engaged by the dial hand when the latter has arrived at the point on its scale dial to again sound the alarm and so on successively. The operation in detail will be 65 understood from the description given in

connection with the description of the individual parts and need not be repeated.

In various ways the details of construction herein shown and described may be modified and still be within the scope of my 70 invention.

It will be understood that the alarm may be sounded or a circuit closed through the operation of the yoke 31 at any desired period during the day or night by simply 75 increasing the number of actuating hands on the alarm dial. I have shown in Fig. 1 but two of these hands, but obviously a greater number may be used and the alarm mechanism tripped with each engagement 80 of a hand with the yoke 31, suitable modification being made in the form of this yoke to adapt it for the different purposes for which the alarm may be used.

I claim as my invention:

1. A time-piece comprising a time train gearing, a main spring for the same, and an alarm train gearing operatively connected with said main spring, a vibratable arm operatively connected with the alarm train 90 gearing, a locking member disposed to be projected into the path of the vibratable arm to engage the same and lock the alarm train of gearing against movement, an alarm dial hand carried by a shaft operated 95 through connections with the main spring, a shaft carrying a pinion meshing with a wheel of the alarm train of gearing to be rotated therefrom, said shaft being provided with a cam-like member to engage 100 and project the locking member into the path of the vibrating arm to stop movement of the alarm train of gearing, and a member carried by the cam-like member shaft and lying in the path of the alarm dial 105 hand to be engaged by said hand to release the cam-like member from the locking member and permit movement of the alarm train of gearing.

2. A time piece comprising a train of 110 gears and an operating spring therefor and an escapement having a vibrating arm, an alarm dial and hands therefor, a pinion meshing with one of said train of gears and having a limited rotary movement independently of said gears, means for normally locking said vibrating arm, means connected with said pinion for normally holding said locking means in its locking position, said locking means being released upon the initial movement of said pinion, and means in the path of said alarm dial hands for operating said pinion at a predetermined period and releasing said locking means.

3. A time piece comprising a train of 125 gears and a main spring therefor, a vibrating arm and pallet for controlling the movement of the gears, a spring positioned to be projected into the path of said vibrating arm to check its vibration, a yoke formed to 130

- normally engage said spring and hold it in the path of the vibrating arm, and a pinion meshing with one of the train of gears for restoring the yoke to engagement with said 5 spring to check the vibrating arm following the release of the spring therefrom.
4. In a time piece, the combination, with a train of gears and a main spring therefor and a vibrating escapement arm, of a member mounted to normally hold said arm against vibration, a yoke for locking said member in position to engage said arm, a pinion connected with said yoke and having teeth meshing with the adjacent gear of 10 said train and having a limited movement independently of said gear for moving said yoke and releasing said locking member.
5. The combination, with a train of gears, an escapement arm and operating main 15 spring, of a post, a pinion secured thereon and having teeth meshing loosely with the teeth of an adjacent gear of said train, a member mounted on said post to engage and lock said escapement arm, the initial movement of said post and pinion moving said 20 yoke to release said locking member and said yoke having means for engaging said locking member and returning it to its locking position when said yoke and pinion 25 have completed a half revolution.
6. In a time piece, an alarm dial graduated for the hours of the day, and indicator 30 hands for said dial, a train of gears and a main spring therefor and an escapement, a vibrating arm and a mechanism connected 35 with said train of gears to be operated thereby to make a half revolution when released, said mechanism including a member for normally locking said vibrating arm and also including means in the path of said alarm 40 dial hands to be tripped thereby for releasing said locking member and said vibrating arm.
7. A time-piece comprising a train of gears and a main spring therefor, a vibrating arm and pallet for controlling the movement of the gears, a locking member disposed to be projected into the path of the vibratable arm to engage the same and lock the train of gears against movement, a dial 45 hand carried by a shaft operated from the main spring, a shaft carrying a pinion meshing with a wheel of the train of gears to be rotated therefrom, said shaft being provided with a cam-like member to engage 50 and project the locking member into the path of the vibrating arm to stop movement of the train of gears, a member carried by the cam-like member shaft and lying in the path of the dial hand to be engaged by said 55 hand to release the cam-like member from the locking member to permit movement of the train of gears, and an actuating arm carried by the shaft of one of the gears of the train and moved from one position to another upon release of the train of gears.

In witness whereof I have hereunto set my hand this 25th day of October, 1917.

ALBERT P. MYER.
